CLOWN BANK OR SIMILAR ARTICLE

Warren O. Dontigney, Meriden, Conn., assignor to The Napier Company, Meriden, Conn., a corporation of Connecticut

Application September 10, 1956, Serial No. 42,880

Term of patent 14 years

(Cl. D34—11)

Fig. 1 is a front elevation of a clown bank or similar article, showing my new design;

Fig. 2 is a side elevation thereof looking from right to left with respect to Fig. 1; and

Fig. 3 is a top plan view thereof.

I claim:

The ornamental design for a clown bank or similar article, substantially as shown.
